Specification of Letters Patent. Patented Jan. 14, 1913.

Application filed February 3, 1912. Serial No. 676,184.

To all whom it may concern:

Be it known that I, CHRISTIAN FREDRICKSON, a citizen of the United States, and a resident of Rice Lake, in the county of Barron and State of Wisconsin, have invented a new and Improved Separator, of which the following is a full, clear, and exact description.

The object of the invention is to provide 10 a new and improved machine which will receive potatoes and the like, and separate the same into various sizes or grades, and at the same time clean the potatoes.

Another object of the invention is the 15 production of improved means which are adapted to receive and transport potatoes or other matter which is designed to be separated, to a separating screen without injury to the potatoes while transporting the same in a continual stream and dumping or forcing 20 the potatoes on to the separating screen while the screen is in operation, so that the motion of the potatoes will be continuous until the same have been forced out or 25 ejected from the machine in different grades.

In constructing a practical embodiment of the invention, an endless conveyer is provided, formed with a plurality of flights having fingers or teeth projecting laterally or transversely therefrom, whereby articles of various sizes may be carried up the conveyer and transported to the desired point without danger of becoming displaced. This conveyer is associated with a receiving 35 hopper formed with an opening adjacent the conveyer so that the articles placed in the hopper will gravitate toward the conveyer. In order to prevent the articles in the hopper from escaping therefrom and yet provide 40 an opening for the passage of the flights of the conveyer, a bar formed with fingers is arranged adjacent the conveyer so that the fingers will project to a point nearly in contact with the conveyer, the 45 fingers connected with the hopper preventing the articles from moving out of the hopper but permitting the free passage of the flights and the fingers projecting from the conveyer. Also associated with the conveyer 50 is a separating sieve arranged to separate the potatoes or other articles in any desired number of grades or sizes, and then

discharge the various grades out through independent chutes.

A practical embodiment of the invention 55 is represented in the accompanying drawings forming a part of this specification, in which similar characters of reference indicate corresponding parts in all the views.

Figure 1 is a perspective view of an embodiment of the invention; Fig. 2 is a section through Fig. 3, taken on the line 2—2 looking in the direction of the arrow; Fig. 3 is a longitudinal vertical section through 65 the separator, the same being taken on the line 3—3 of Fig. 5; Fig. 4 is a detail fragmentary side view of a clutching and unclutching mechanism; Fig. 5 is a top plan view of the structure shown in Fig. 1, the 70 same being shown on a larger scale; and Fig. 6 is a section through Fig. 3 on the line 6—6.

Referring to the accompanying drawings by numerals, 1 indicates a framework provided with any suitable number of uprights 2. Arranged on the frame 1 and secured to some of the uprights 2, an elevator or conveyer 3 designed to raise potatoes or other articles from a hopper 4, to a higher 80 elevation and then move the same a short distance substantially horizontally, and finally dump the potatoes or other articles on a separating screen device 4' which is moved back and forth by suitable mechanism, hereinafter more fully described, for causing the proper separation of the potatoes or other articles into different sizes or grades, which are discharged either into the hoppers 5 and 6, or out at the end 7 90 into any desired receptacle provided at that point. The conveyer 3 is formed with side members 8 and 9, and a bottom 10. A pair of chains 11 and 12 are arranged to move over the bottom 10 and to be supported by 95 sprocket wheels 13—13, 14—14, 15—15, and 16—16, the sprocket wheels 14—14 acting as the driving sprockets for moving the chains. These chains are connected together at spaced intervals by flights 17 provided with fingers 18 extending therefrom at substantially right angles to the general direction of the chains. These fingers are made of some considerable length in order to en-

size potatoes or other articles which it is desired to raise and separate. The machine is adapted especially for receiving and separating potatoes and will be described as a machine for this purpose, but it will be understood that other articles may be separated into different sizes or grades equally well.

When the chains are moving, it is necessary for the flights with their fingers to pass through the bottom of hopper 4 so that an opening 19 is provided in the bottom 20 of hopper 4. In order to prevent the potatoes from dropping out of the hopper 4 when the opening 19 is not closed by a finger 17, a bar 21 is rigidly connected with the hopper 4, the same being formed with a plurality of fingers 22 which substantially fill the opening 19, but permit the free passage of the fingers 18. The hopper 4 is removably connected with the conveyor or elevator 3 by means of pins 23 and blocks 24, fitting into retaining sockets 25 and 26, respectively. From an examination of Fig. 3 it will be observed that the chains 11 and 12 do not move in a straight line to the upper point, and then back again, but move in a straight line to an upper point and then move horizontally for a short distance in order to transport the potatoes to the screen 4' without causing the same to have a considerable fall between the discharge point of the conveyor and the screen. The chains on their upward movement pass over the sprocket wheels 14-14, around the sprocket wheels 15-15, and back over the sprocket wheels 16-16. This produces an overhanging substantially horizontal portion of the conveyor under which projects the screen 4'.

The screen 4' is swung on links 27 and 28 at its front or intake end and at its opposite end is arranged to freely slide on blocks 29 and 30. The lower end of the links 27 and 28 are pivotally connected with the screen 4', and the upper ends of these links are mounted on a shaft 31 which carries the sprocket wheel 15-15. The lower or discharge end of the screen 4' is supported by the blocks 29 and 30, which in turn are supported by brackets 32 and 33, each of which is formed with a slot 34 through which a bolt 35 is passed. By the provision of the slots 34 the brackets 32 and 33 may be adjusted vertically for controlling and adjusting the angle of operation of the screen 4', which has been found desirable as various kinds of potatoes, and various other articles require different degrees of pitch for properly separating the same. The screen 4' is provided with side members 36 and 37 which are preferably inclined toward each other at the discharge end, as clearly shown in Fig. 5, in order to more easily cause the potatoes to discharge into a sack or other receptacle. Connected

with the sides 36 and 37 is a solid or imperforate bottom 38. The bottom 38 is cut away at 39 and 40. The cut away or opening 39 is covered by a wire mesh 41, but the cut away portion or opening 40 is left without any covering. Spaced above the bottom 38 is a wire mesh 42 which is rigidly secured to the side members 36 and 37 in any desired manner so as to move therewith. The wire mesh 42 is of coarser grade than the wire mesh 41 so that the medium size and small potatoes, as well as the dirt, will pass through the mesh 42 on to the bottom 38 and thence move over the mesh 41. The dirt and small potatoes will pass through the wire mesh 41 into a bin 43. The medium sized potatoes will move on downward and pass through the opening 40 and drop into a bin 44, from which they will pass out of the machine after having engaged the inclined bottom 45. The potatoes and dirt in the bin 44 are designed to engage the inclined bottom 46 and pass out of the machine. The inclined bottoms 45 and 46 are arranged to rest upon a plurality of supporting bars 48, and may be adjusted so as to eject or guide the potatoes out on opposite sides of the machine, or on the same side. In this way the dirt and small potatoes, and the medium sized potatoes are moved to different points of discharge, while the large potatoes are caused to move downward and finally be guided out the lower end of the screen. In the drawings the machine is shown designed to separate the potatoes into three grades, but it will be evident that additional grades may be provided for, by the provision of additional bins and the provision of additional screens, similar to screen 4', but of a different mesh.

Connected with the bottom 38 is a shaker arm 49 which is also pivotally mounted on a crank shaft 50 journalized in brackets 51 and 52. The brackets 51 and 52 are each provided with a slot 53 adapted to receive one or more bolts for firmly securing the brackets in position. By providing slots 53 in the brackets, an adjustment may be given to the shaft 50 for tightening the chain 54. The crank shaft 50 carries at one end a sprocket wheel 55, over which passes the chain 54, the chain 54 also passes over the sprocket wheel 56 rigidly secured to a shaft 57. The shaft 57 extends entirely through the machine and carries a gear wheel 58 on the end opposite the sprocket wheel 55. The gear wheel 58 is arranged to mesh with a pinion 59. The pinion 59 is mounted upon a stub shaft 60 rigidly secured to a lever 61. The lever 61 is pivotally mounted on a shaft 62 so that when the lever is moved back and forth it will move on the arc of a circle, with its center coincident with the center of the shaft 60. The chain 50 is adapted to con-

tinually mesh with the gear wheel 58. The gear wheel 58 is rigidly secured to the shaft 63, which shaft carries the power pulley 64 and is adapted to continuously rotate as long as the engine or other motive power is in operation. However, it is not necessary for the separator to operate even if the power pulley 64 is moving.

When the pinion 59 is meshing with the gear wheel 62, power will be conveyed from pulley 64 to shaft 63, sprocket wheel 58, pinion 59, and from thence to gear wheel 62, and to the other moving parts of the separator. When the pinion 59 is moved to the dotted position shown in Fig. 4, the power pulley 64 is disconnected from the moving parts of the separator so that the separator will stop notwithstanding the fact that the pulley 64 is continually moving. In order to throw the pinion 59 into and out of mesh with gear wheel 62, the lever 61 has pivotally connected therewith, a link 65 which is pivotally connected at its opposite end with a pivotally mounted lever 66. The lever 66 is designed to be positioned either in a notch 67 or a notch 68 in rack 69. When the lever 66 is in notch 68, the power is connected to the machine so that the same will operate, and when the lever 66 is in notch 67 the power is disconnected from the operating parts of the machine. By this construction and arrangement of means for throwing the machine into and out of operation, the engine or other power need not be shut down when it is desired to stop the separator.

Arranged at one end of the machine are a pair of L-shaped levers 70 which carry a cross bar or axle 71, on which are mounted traction wheels 72 and 73. The lower end 40 of the levers 70 are pivotally connected by bolts or other suitable means to the frame 1, so that when the upper end of the levers are moved downward and caused to engage notches 74—74, the front of the machine will 45 be supported by the wheels 72 and 73. This will permit the machine to be shifted or moved about more easily.

In operation the potatoes or other matter being separated is fed into hopper 4 from a wagon or other source of supply. As the machine continues to move the flights 17 and fingers 18 will successively engage and lift predetermined quantities of the potatoes and finally dump the same upon the screen 4.

At the time that the potatoes are dumped on the screen 4, the same is oscillated and moved back and forth by the crank lever 50. By reason of the shaking action of the screen 4 and the angle at which it is placed, the potatoes will move downward toward the lower or discharge end, and will gradually be separated, the large potatoes passing out the lower end of the screen, the medium sized potatoes through the opening 40, and the smaller potatoes and dirt through the

screen 41. As long as the hopper 4 is kept supplied with potatoes and power is provided to the machine the same will continually operate and continually separate potatoes into different sizes or grades without any assistance from the operator.

Having thus described my invention, I claim as new and desire to secure by Letters Patent:

1. In a separator of the class described, the combination of an elevator, a separating screen adapted to receive articles from said elevator, said separating screen comprising a body portion formed with a plurality of aligned apertures therein, a wire mesh covering substantially all of said body portion and spaced therefrom so that a certain grade or size of matter may pass through the wire mesh on to the body portion, a finer wire mesh covering one of said apertures whereby articles passing through said first-mentioned wire mesh are adapted to pass over said second-mentioned wire mesh and be divided into a plurality of grades thereby, the finer grade passing through the second-mentioned wire mesh and into the aperture, and means for giving said screen a back and forth movement.

2. In a separator of the class described, the combination of an elevating device, a screen for receiving articles from said elevating device, said screen being formed with a body portion having a plurality of apertures in the bottom thereof, a wire mesh arranged in one of said apertures, a wire mesh of coarser grade arranged above the bottom of said body portion and covering the first-mentioned wire mesh and all of said apertures, means for supporting the lower end of said screen, swinging means for supporting the upper end of said screen, and means for moving said screen in a back and forth direction whereby matter placed on said wire mesh arranged above the bottom of said body portion will move over the wire mesh, and the finer matter will pass through said wire mesh on to the bottom of said body portion and on to said wire mesh arranged in one of said apertures, and from thence the coarser matter will pass over said last-mentioned screen into one of said apertures and the finer matter will pass through said last-mentioned screen.

3. In a separator of the class described, the combination of a base, an elevator arranged on said base, a wire mesh for receiving articles from said elevator, said wire mesh projecting beneath a substantially trough-shaped housing for supporting said wire mesh formed with a plurality of apertures in the bottom thereof, a wire mesh of finer grade than the first mentioned wire mesh positioned in the opening in said bottom nearest said elevator, means for driving said elevator, means for moving said trough-

shaped housing and said wire mesh in a back and forth movement, and means for receiving the articles separated by said first mentioned wire mesh, said trough-shaped housing, and said second mentioned wire mesh and guiding the same to distinct discharge points.

In testimony whereof I have signed my name to this specification in the presence of two subscribing witnesses.

CHRISTIAN FREDRICKSON.
